(57) CLAIM

The ornamental design for a “food serving pan,” as shown and described.

DESCRIPTION

FIG. 1 is a left side elevational view of a “food serving pan” showing my new design, the right side being a mirror image thereof;

FIG. 2 is a top plan view thereof;

FIG. 3 is a rear elevational view thereof;

FIG. 4 is a bottom plan view thereof;

FIG. 5 is a front elevational view thereof; and,

FIG. 6 is a perspective view thereof.
